UNITED STATES PATENT OFFICE.

JOHN ALEXANDER LESLIE, OF ANTELOPE, OREGON.

HAMMER.

1,089,234.

Specification of Letters Patent.

Patented Mar. 3, 1914.

Application filed August 5, 1913. Serial No. 783,108.

To all whom it may concern:

Be it known that I, JOHN A. LESLIE, a native-born citizen of the United States, residing at Antelope, in the county of Wasco 5 and State of Oregon, have invented new and useful Improvements in Hammers, of which the following is a specification.

The invention relates to an improvement in hammers and particularly to a hammer 10 of that type in which the driving head is capable of adjustment from its normal position at right angles to the handle to a position in line therewith, whereby in such latter position the hammer is peculiarly adapted 15 for extracting nails without the usual bending thereof.

The main object of the present invention is the provision of a hammer in which the driving section is rotatably mounted upon 20 the head proper, so that it may be moved to a position at right angles to the handle or into a position in alinement therewith, means being provided whereby the driving section may be locked in either position 25 against the possibility of accidental movement in the use of the tool.

The invention in its preferred form of details will be described in the following specification, reference being had particularly to 30 the accompanying drawings, in which:—

Figure 1 is a side elevation of a hammer constructed in accordance with the invention, the handle thereof being partly broken away. Fig. 2 is a top plan view thereof. Fig. 3 is a sectional view on the line 3—3 35 of Fig. 1. Fig. 4 is a detail perspective view of one of the sections of the hammer head. Fig. 5 is a view similar to Fig. 3 showing a slightly modified form.

40 In the accompanying drawings, the improved hammer comprises the usual handle 6 on which is secured a head *a* which, except for the detail of my improvement, is of the usual construction. The head presents what 45 may be termed a fixed section 7 and a movable section or driving butt 12, the former having the usual socket 8 to receive the end of the handle and being formed with a laterally extending usual type of extracting 50 claw 9.

That portion of the section 7 in line with

the handle and remote from the claw 9 is cut away to reduce the thickness of the head as at 10, the wall of the cut away portion being partially rounded to form a seat. The 55 hammer section 12 is provided at the end remote from the striking head 13 with spaced parallel wings 11 to snugly fit the cut away portion and ride against the rounded wall thereof. The head wings are 60 provided with registering openings 13' and 14, one of the openings 14 in the head being plane and countersunk and the other interiorly threaded. A pivot bolt 15 is passed through the openings to pivotally support 65 the hammer section, said bolt having a head 16 to fit in the countersunk opening 14 and terminally threaded to coöperate with the other opening 14. The head section 7 is 70 formed adjacent the cut away portion 10 and preferably below the same with an enlargement 17 having a longitudinal bore 18 to receive a coil spring 19, a locking bolt 20 being slidably mounted in the bore and bearing at one end upon the spring, the 75 opposite end of the bolt being designed to engage either of two radial recesses 21 in the periphery of the adjacent wing 11, whereby the hammer section 12 may be locked in either of its two operative positions. The bolt is preferably provided with a projection 22 serving as a means for conveniently operating the bolt when it is desired to change position of the hammer section. The head section 7 is further provided 80 with a laterally projecting lug 22' serving as a stop to limit the position of the hammer section when the latter is in normal or right angled relation to the handle.

In the form illustrated in Fig. 5 of the 90 drawing the section 7' has secured to one side thereof a leaf spring 23 by means of a rivet 24 which engages one end of said spring. The other end of said spring has secured thereto, by means of a suitable 95 fastener 25, a block 26 which is adapted to normally engage in the notch 27 formed in the section 7' and also engage in one of a pair of recesses 28 in the wings 11' and formed similar to the recesses 21. The leaf 100 spring 23 is slightly extended beyond the block 26 to provide a finger catch 29 where-

by said block may be readily disengaged from the sections to permit of the adjusting of the same.

What is claimed is:—

5. A hammer including a head, an independent driving butt forming part of said head, said butt being pivotally connected to the head for adjustment to position the operative end of said butt in either of two right

angularly related positions, and means for locking the butt in either of such positions with relation to the head.

In testimony whereof I affix my signature in presence of two witnesses.

JOHN ALEXANDER LESLIE.
